REFRIGERATED LOCKER

Frank W. Knowles and Hawley A. Dudley, Seattle,
Wash.; said Dudley assignor to said Knowles

Application January 23, 1942, Serial No. 427,907

4 Claims. (Cl. 312—149)

1

The present invention relates to improvements in refrigerated lockers. In particular, the present invention relates to improvements in a type of refrigerated chamber having a large number of small compartments which may be rented separately to different people.

In the past, refrigerated lockers have been unsatisfactory because in some instances the user has had his whole body subjected to the refrigerating temperatures, and where such has not been the case, the equipment has been inadequate for large commercial installations.

It is an object of the present invention to provide a refrigerated locker which will have a drawer of large dimensions, and which drawer may be easily moved in and out of a refrigerated chamber.

Another object of the present invention is the provision of a refrigerated housing having opposed openings, an elongated drawer adapted to slide endwise through said openings, a closure for each of said openings, each of said closures being larger than its respective opening and overlying said opening, and means for engaging each of said closures with either said housing or said drawer while disengaging it from the other.

Devices constructed in accordance with the above, and which will attain the objects of the present invention, are hereinafter described in detail and shown in the accompanying drawings wherein:

Figure 1 is an elevational view of a housing having two tiers of insulated closures behind which are their respective drawers.

Figure 2 is a sectional end view on the line 2—2 of Figure 1.

Figure 3 is an elevational view of the locking mechanism taken on the line 3—3 of Figure 2.

Figure 4 is a sectional plan view of the locking device taken on the line 4—4 of Figure 3.

Figures 5, 6, and 7 are views corresponding to a portion of Figure 3 and showing the locking mechanism in various positions.

Figures 1 and 2 show a refrigerated housing 1 which may be refrigerated by any suitable means for refrigerating and circulating air therethrough. The housing 1 comprises an insulated top 2 and bottom 3 with insulated side frames 4, 5, which have therein tiered openings 6 closed by suitable closures 7 which overlie the openings and fit against the side frames 4, 5. Inside the housing 1 are arranged tiers of shells 8 one upon another. These shells are formed as tubes which are square in cross section, and which extend across the housing from side to side with their 55

2

open ends abutting against the inside of the housing. The end openings of the shells are arranged in alignment with the openings 6 closed by the insulated doors 7. Each shell 8 supports therein a rectangular and elongated drawer 9 which has its sides and ends closed as well as the top, with the exception of a plurality of small openings having removable locker closures 10, each one of which gives access to an individual locker. Each locker in a drawer 9 is separated from its contiguous lockers by a partition 11. The tubular construction of the drawer and the partitions separating the individual lockers gives a strong and rugged device. The drawer may be constructed of half-inch plywood, have a cross section two feet square, and be sixteen feet long. Such a construction will hold about sixteen hundred pounds of produce and operate in a very satisfactory manner. Each of the drawers may be supported upon suitable rollers 12 placed thereunder and bearing at their ends in the side walls of the shell. The rollers at the end of the shell may have additional support and bearing surface by the provision of vertical uprights 13 placed alongside the ends of each tier of shells. An end roller is, at times, called upon to support the total weight of the drawer. A top or hold-down roller 14 is provided and placed centrally of the shell. This hold-down roller will prevent the inner end of the locker from tipping up as the other end is withdrawn. The sides of the shell may be provided with openings 15 for the circulation of refrigerated air to the interior of the shell and around the drawer. The tiers of shells may be spaced apart to provide vertical air-circulating spaces 16, or ducts. Also the top and bottom 2, 3 of the housing 1 may be spaced from the top and bottom of the tiers of shells to provide upper 17 and lower 18 air-circulating ducts, so that refrigerated air may be circulated both along the tiers and up and down between them. Such a construction will allow produce placed in the drawers to be rapidly refrigerated by the circulation of cold air in the circulation ducts 16, 17, 18, and through the openings 15 in the shells and around the drawers. The closed and imperforate ends 19 of the drawers are spaced from the inside surface of the closures 7 a distance of four or five inches. The sides of this space between the drawer ends 19 and the closures 7 are closed by the sides of the openings 6 in the side frames 4, 5. This space between the closures and the drawer ends forms, in connection with the flexible seals 20 which contact both the inner portion of the frame and

the drawer, a pocket. As a drawer end enters this pocket it will compress the air therein, and this compressed air will act as a cushion to absorb the inertia forces of the drawer as it slides or is pushed home into position in the insulated housing 1.

The locking mechanism which is adapted to hold the closures 7 to the side frames or, optionally, to the ends of the drawer, is best shown in Figures 3 to 7 inclusive.

The back of each closure 7 carries a locking mechanism which is placed in the air check pocket between the back of the closure and the end of the adjacent drawer. The sides of the frame openings 6 are provided with suitable frame bolt-sockets 30 adapted to receive the ends 15 of frame locking bolts or locking members 31. The ends of the drawers are provided with suitable drawer bolt-sockets 32 which in the present instance are shown in the form of strap loops attached to the ends 19 of the drawers. These drawer bolt-sockets 32 are adapted to receive the ends of drawer locking bolts 33 or a portion of the locking members. As shown in the drawings, the drawer locking bolts are carried by the frame locking bolts 31 in the form of an offset finger attached thereto. The two separate bolts and sockets are arranged so that as a frame locking bolt is about to leave its socket, the drawer locking bolt carried therewith is just entering its respective socket. It will thus be seen that if the proper sockets are in registry with the proper bolts, the bolts will not be entirely unlocked from the sockets in the frame and the drawer at the same time. The inner ends of the bolts are carried on bolt plates 34. The bolt plates are connected by means of a tie-bar 35 so that all the bolt plates will operate together. The bolt plates 34 are pivoted by pins 36 on mounting brackets 37 that space them away from the back of the closure 7. The outer ends of the bolts are supported in openings in suitable brackets 38 and 38A. The bolt supporting plates 34 may be rotated about their pivots 36 by the insertion of an operating key 39 (Figure 8) through an opening 40 in the closure 7, which key will fit in a socket 41 fixed on a pivot pin 36 which is in turn secured to a bolt plate 34. Rotation of a socket 41 will rotate the attached bolt plate which, through the tie-bar 35, will rotate the other bolt plate and thus all the bolts will be actuated and the closure 7 may be secured to either the drawer or the insulated housing.

In order to safeguard against removal of a closure 7 from a drawer when the drawer is extended out of the refrigerated chamber, or to prevent removal of a closure from the frame when the drawer is not in registry to receive the drawer locking bolt 33, there is provided a registry locking means which will prevent operation of the bolt if the proper sockets are not in registry and adapted to receive the bolts as they are moved from one set of sockets to the other. The registry locking means has as its principal component a feeler pin 50 which is of such a length that one end will, when the closure is in place, just touch the side of the closure opening 6 and the other end of the pin will just touch a stop 51 which is secured to the end 19 of the drawer. The feeler pin may be made in the form of a flat bar with its face parallel to the drawer and closure, and the pin may be supported at one end in the bolt bracket 38A and in the other end in a feeler pin bracket 52. The openings in brackets 38A and 52 which support the feeler pin are elongated to

allow the pin to move from and toward the adjacent bolt. However, the bracket openings are narrow enough to prevent turning of the pin. As long as the feeler pin 50 is held between its stops, a cam 53 secured to an adjacent bolt and the cam follower plate 54 secured to the feeler pin, will act, upon motion of the bolt, to give the feeler pin motion toward and from the bolt. The bracket openings for the pin will allow this motion. However, if the stop for either end of the feeler pin is not in position, then the cam as it moves in the direction of that stop will, through the cam follower plate 54, cause movement of the feeler pin 51 in that direction. When the feeler pin 50 is held between its stops, there is spaced from each side of the follower plate 54, about the thickness of the plate, a locking lug 55, 57 to limit movement of the follower plate and feeler pin when the stops are not in position to do so. These locking lugs are both mounted on the same plate base which is secured to the back of the closure. Each of the locking lugs has a projecting lip 58, 59 opposite to the other and just above the cam follower when such is depressed. These lips form a narrow slot slightly wider than the follower plate 54. If the movement of the feeler pin is to the right, as shown in Figure 6, then the cam follower plate 54 will move against the right hand cam follower plate locking lug 55 and then the cam follower plate will begin to move away from the bolt but the upper edge of the plate will lock under the lip 56 attached to the upper part of the right locking lug. This will prevent upward movement of the cam plate and prevent further movement of the cam and the bolt carrying it. This will prevent withdrawal of the bolt from the frame socket. This in turn will prevent removal of the door of the closure from the frame in the absence of the drawer and its stop 51. The action is the same if the drawer locking bolts 33 are being withdrawn from their respective sockets. The cam 53 will move to the left and if the frame acting as a stop is not in position the cam follower plate will then bear against the left locking lug 57 and lock under its lip 58, and will thus prevent sufficient motion to withdraw the drawer locking bolt from its respective socket.

The operation of the above described device is as follows: With the drawers all in position and filled with produce, refrigerated air may be circulated in the upper and lower air passageways 17 and 18 and down between the tiers through the vertical air ducts 16 and around the drawers 9 by passage through the openings 15 in the shells 8. This circulation of refrigerated air will serve to freeze and keep frozen such produce as may be contained in each of the individual lockers. Of course it is desirable when large amounts of produce are to be placed in a locker that the produce be previously frozen in a separate compartment, such as a quick-freezing compartment where the temperature may be maintained much lower than necessary in a storage locker, and where the circulation may be more rapid to effect a quick freezing. Normally, all the insulated closures 7 are locked into the housing side frames 4, 5 and are free from the drawers. When it is desired to remove a drawer from the housing, a key 39 is inserted in the key-opening 40 in the closure 7, and the locking mechanism is operated to unlock the closure from the frame and lock it onto the drawer. The handle on the door may then be pulled upon and the closure and drawer moved outwardly from the housing. The drawer

is never removed from the housing more than a little less than about half way, leaving the half remaining in the housing to counterbalance the half removed. This removing of only half of the drawer at a time by movement in either direction to either side of the housing, greatly simplifies the construction in that the strains on the drawer are greatly reduced and the problem of providing suitable rollers or bearings upon which the drawer moves is much simpler. This is particularly so, in view of the fact that these drawers are loaded with weights of sixteen hundred pounds or more of produce. Entrance to individual lockers in the drawer may be had through openings in the top of the drawer which are closed by separate closures 10 and locks. When the patron has removed or placed in his particular locker the desired material, the drawer may then be returned to its closed position, the closing shock being absorbed by the air check pocket at the inner end of the drawer, and the locking mechanism operated to secure the closure to the frame again and release it from the drawer. The closure key upon being inserted in the opening 48 will fit into a socket 41. Rotation of the key will then turn this socket and the bolt plate to which it is connected. This in turn will rotate one bolt plate 34 and through a tie-bar 35 will rotate the other bolt plate. Rotation of the bolt plates will operate the bolts in and out of their sockets. As the frame bolts are withdrawn from their sockets, the drawer locking bolts will be inserted into their sockets, and vice versa. Removal of the bolts from one set of sockets if the other set is not in proper registry is prevented by the feeler pin 51 which is designed to have its ends ride against stops carried by the frame and the drawer. If either stop is not in position, a camming device will serve to lock the bolts so that they can not be moved.

The space 16 between the tiers of shells 8, and the overlap of the closures 7 from the edges of the openings 6 is such that the space between the edges of closures in adjacent tiers is considerably less than the thickness of an insulated closure 7. The closures may be sealed to the face of the housing by inserting a felt sheet between the closure and the housing. The overlap of the closure should be equal to at least the thickness of the closure, so that the insulation value across the face of the overlap will be equal to the insulation value of the thickness of the closure. If this overlap of the closure is six inches, then the distance between the sides of the drawers in adjacent tiers is a little over twelve inches, thirteen and one-half. This distance is sufficient room to provide for the shell walls and still leave ample room for air circulation in the vertical passageway 16. If the closures were to be hinged to the side frames 4, 5, it would be difficult, if not impossible, to open adjacent closures in opposite tiers without interference, let alone to open such adjacent drawers and withdraw adjacent drawers at the same time. Tapered or plug-type closures without special offset hinges would have to be opened more than ninety degrees in order to clear the drawer as it was being withdrawn. The present construction of overlapping closures enables the tiers and closures to be set closely together and eliminates the necessity for using hinges. The provision of oversized air ducts between the tiers is costly in the first instance, as well as in maintenance, due to the poorer circulation and the increased heat transfer. The use of such overlapping insulated closures is very desirable.

even if the drawer is to be pulled in only one direction, that is, it leaves the housing through only one opening.

Having thus described the construction and operation of our device, we claim:

1. In a cabinet structure, a housing including a side wall, said side wall having an opening therein, a drawer supported within the housing for movement outwardly through said opening, a closure member for said opening, a locking member moveably carried by the closure member, said housing having a socket therein adjacent said opening for receiving a portion of said locking member and maintaining the closure member in position closing said opening, a keeper carried by an end of the drawer, and said keeper being positioned to receive therein a portion of the locking member as it is withdrawn from the socket to detachably secure the closure member to the drawer.
2. In a cabinet structure, a housing including a wall, said wall having an opening therein, a drawer supported within the housing and adapted to be moved endwise outwardly through said opening, a closure member for said opening, a plurality of locking members mounted for sliding movement on the inner face of the closure member, said housing having a plurality of sockets therein for receiving portions of said locking members and maintaining the closure member in position closing said opening, a plurality of keepers mounted on the end of the drawer and positioned to receive therein portions of said locking members as the same are withdrawn from the sockets to releasably secure the closure member to the drawer.
3. In a refrigerator cabinet, a housing including opposite side walls, said side walls having aligned openings therein, a drawer within the housing supported to be moved outwardly through either of said openings, a closure member for one opening, a second closure member for the other opening, a locking member mounted for movement on the first closure member, a locking member mounted for movement on the second closure member, said housing having a socket therein adjacent each opening for receiving portions of the respective locking members and maintaining the closure members in positions closing said openings, a keeper carried by each end of the drawer, and each keeper being positioned to receive therein a portion of the associated locking member as it is withdrawn from the socket to detachably secure the associated closure member to the drawer.
4. In a refrigerator cabinet, a housing including opposite side walls, said side walls having aligned openings therein, a tubular shell having open ends supported within the housing in register with said openings, an elongated drawer arranged within said tubular shell and adapted to slide endwise therein and outwardly through either of said openings, a closure member for each of said openings, movable locking members carried by each closure member, keepers on each end of said drawer, said housing having sockets therein for receiving portions of said locking members to maintain the closure members in positions closing said openings, and said keepers being positioned to receive therein other portions of said locking members as they are withdrawn from said sockets.
